UNITED STATES PATENT OFFICE.

HOWARD D. COLMAN, OF ROCKFORD, ILLINOIS, ASSIGNOR TO HOWARD D. COLMAN, LUTHER L. MILLER, AND HARRY A. SEVERSON, COPARTNERS DOING BUSINESS AS BARBER-COLMAN COMPANY, OF ROCKFORD, ILLINOIS.

WARP-HANDLING MACHINE.

1,306,138.

Specification of Letters Patent.

Patented June 10, 1919.

Application filed February 14, 1916. Serial No. 78,133.

To all whom it may concern:

Be it known that I, HOWARD D. COLMAN, a citizen of the United States, residing at Rockford, in the county of Winnebago and 5 State of Illinois, have invented certain new and useful Improvements in Warp-Handling Machines, of which the following is a specification.

This invention relates to machines for operating upon warps, as, for example, warp-uniting machines, warp-drawing machines and lease-picking machines, and has particular reference to machines which are intended to operate upon striped warps.

15 When drawing a striped warp through loom harnesses, it is essential that the threads be selected in proper sequence, in order that the different colored threads shall be drawn through the proper eyes of the 20 harnesses. Similarly, when uniting a striped warp to a section of old warp, it is essential that the threads of the new warp be tied to the corresponding threads of the old warp. As there is a possibility that 25 threads may be crossed or improperly leased or missing in one or both of the warps, it is important that the operation of the thread selectors be carefully watched, and that any necessary corrections be made before the selected thread or threads are placed in the 30 knotter.

The object of this invention is to provide means to assist the operator of a warp drawing machine, warp-tying machine, lease-picking machine or other warp-handling machine, to discover errors in the selection or arrangement of the threads, so that the necessary correction may be made.

In the accompanying drawings, Figure 1 40 is a fragmental side elevation of a warp-tying machine embodying the features of this invention. Fig. 2 is a fragmental horizontal sectional view taken in the plane of dotted line 2—2 of Fig. 1, but upon a somewhat larger scale. Figs. 1 and 2 illustrate the mechanism in two different positions. Fig. 3 is a view taken approximately in the plane of dotted line 3 of Fig. 4. Fig. 4 is a view taken in the plane of dotted line 50 4 of Fig. 3.

The invention is herein illustrated in connection with a warp-tying machine similar to the one fully illustrated and described in application Serial No. 26,997, filed May

10, 1915, by Thomas E. Bingham and Earle 55 D. Parker and in British Patent No. 5,574, of 1915. As reference may be had to the patent to be issued upon that application and to said British patent for a full understanding of the construction and operation 60 of the warp-tying machine, I have herein illustrated only so much of said machine as coacts directly with the present invention.

The two warps to be united are supported horizontally, one above the other, in suitable clamps, one of the clamps for the new warp being shown at 77 in Fig. 2.

The particular devices herein illustrated for selecting individual threads from the warps are designed to select threads from 70 an end-and-end lease, the threads of each warp being leased over two rods 128. Fig. 1 shows one of the lease rods for each warp. Fig. 2 illustrates the two lease rods for the lower or new warp. The rods 128 are supported at one end by suitable means not herein shown, but fully disclosed in said Bingham & Parker application. The other ends of the lease rods 128 are supported upon the carriage 136 on which is mounted 75 the selecting and uniting mechanisms. The carriage is arranged to travel upon a guide 137 on the bed of the machine.

Power is transmitted to the mechanisms on the carriage 136 by means of a shaft 138 85 (Fig. 1) which is supported by the bed of the machine. Said shaft may be driven in any suitable manner.

Upon the carriage 136 is a bearing 143 in which is rotatably mounted a sleeve 144, 90 said sleeve being slidably mounted upon the shaft 138. Fixed to the sleeve at opposite sides of the bearing 143 are a pinion 145 and a bevel gear 146. The pinion 145 actuates the thread-selecting mechanism, while the 95 bevel gear 146 actuates the remaining mechanisms mounted on the carriage 136.

Power is transmitted from the shaft 138 to the sleeve 144 by means comprising a clutch member 147 splined to the shaft and 100 slidably therealong, the member 147 being caused to travel with the carriage 136 by a bracket 148 fixed to the carriage and engaging in a groove 149 in the clutch member. On the sleeve 144 is splined a clutch collar 150 which is provided in one end with notches 151 to receive a pin 152 set in the clutch member 147. A hand lever 153 piv-

oted to the carriage at 153^a has a forked lower end that engages the clutch collar 150. The spring 153^b normally holds the collar 150 out of engagement with the member 147.

For each warp, there are provided two selectors 154 operating at opposite sides of the point where the threads cross each other between the lease rods 128. Each selector is 10 fixed to a tubular stem 155 which is mounted for rocking movement in a support 156 on the carriage 136. The selectors for the new warp operate simultaneously with those for the old warp, one thread from the new warp 15 and one thread from the old warp being simultaneously selected for presentation to the uniting mechanism.

As shown in Fig. 1, the selectors for the new warp are located rearwardly of the old 20 warp selectors, in order to avoid interference between the selectors as they oscillate, and so that the selected old-warp thread shall be spaced away from the selected new-warp thread when the latter is in operative relation to the color-indicating means herein-after described.

In the present embodiment, the uniting mechanism consists of a knotter. Any suitable form of knotter may be employed. 30 That herein shown comprises a rotatory tying bill 25 similar to the one fully described in Patent No. 959,592, dated May 31, 1910, said bill being provided with shearing edges whereby the threads are sheared after the 35 loops of the knot have been formed. The tying bill is continuously rotated by means fully described in the Bingham & Parker application.

The threads selected from the warps by 40 the selectors 154 are moved to the knotter by four carry-in fingers only three of which are shown in the present drawings. The finger 191 and a corresponding finger (not shown) act upon the upper warp thread, and the fingers 192 and 193 operate on the lower warp thread. The fingers 191 and 193 are located at one side of the knotter, while the finger 192 and the finger which is not shown herein are at the opposite side. Said fingers have 45 forked ends adapted to engage the threads. The means for actuating the carry-in fingers is fully disclosed in the Bingham & Parker application and therefore need not be herein described. It may be stated, however, that 50 said actuating means includes relatively stationary plates 202 (one for each carry-in finger), each plate having a cam groove 198 therein.

The waste ends, namely the thread portions sheared off by the tying bill 25, are 60 drawn out of the way by a hook 218. The shank of said hook is slidably and pivotally supported upon a relatively stationary stud 219 which extends through an elongated 65 opening 221 in said shank. The hook 218 is

pivoted to a crank 222 fixed to a constantly rotating shaft 174.

The practical applications of this invention (in so far as warp uniting is concerned) will be better understood if it is first 70 stated that it is a necessary condition that two warps, in order to be united, must be of the same draft (*i. e.*, the same arrangement of the threads in the harnesses), but they need not be of the same color pattern; and it 75 is the purpose of this invention to furnish a check or guide as to the correctness of selection of the threads of the new warp when they are not of the same color pattern as the old warp.

In tying a striped warp to a section of an old warp, the operator must take care that the threads of the new warp are selected in accordance with the desired color pattern. 80 As the threads of the old warp are leased, the old warp threads will be selected in accordance with the desired weave, assuming 85 that no threads are missing or crossed or improperly leased. Therefore the operator's task is to see that at each pick a single 90 thread is selected from the old warp and a single thread of the proper color is selected from the new warp. To assist the operator 95 in determining that threads are being thus selected, there is provided means for displaying in proximity to the selected new-warp thread a colored element corresponding in color to the color of thread which should have been selected by the new-warp 100 selectors 154. If therefore the color of the selected new-warp thread does not correspond to the color of the aforesaid element, the operator immediately perceives the 105 existence of a defect or error, whereupon he stops the traveling mechanism and makes 110 the necessary correction. In practice, the operator keeps his hand on the lever 153 while the traveling mechanism is running, and removes his hand from the lever as soon 115 as he discovers an error, the spring 153^b immediately throwing out the clutch 147—150 as soon as the operator releases the lever 153.

In the present embodiment, the means for indicating to the operator the order in which the various colors of the pattern should be 115 selected comprises an endless band 223 which is moved step by step and which is carried by two flanged rollers 224 and 225. The roller 224 is fixed upon a shaft 226 (Fig. 4). The roller 225 is mounted upon a pivot 227 120 which may be secured in adjusted position upon a slotted bracket 228. On the periphery of the roller 224 are driving studs 229 (Fig. 4) that enter perforations 230 (Fig. 2) in the band 223. The roller 224 is intermittently rotated by a pawl 231 (Figs. 2 and 3) pivoted on a lever 232 and engaging a ratchet wheel 233, the latter being fixed on the shaft 226. The lever 232 is pivoted on 125 said shaft and has a roller stud that is held 130

in contact with a cam 234 on constantly rotating shaft 210 by a spring 235. A brake band 236 prevents movement of the band through momentum. 237 is a plate overlying the color band, said plate having a sight opening 238.

The outer side of the band 223 is provided in any suitable way with transverse stripes corresponding in color to the colors of the threads of the new warp. The unit width of the stripes on the band 223 may be, say three-sixteenths of an inch, the length of each movement of the band being the same as the unit width of the stripes; thus for two adjacent threads of the same color the band would have a stripe of that color three-eighths of an inch wide. If the next stripe in the pattern was made up of four threads, there would be a stripe three-fourths of an inch wide of the same color as the stripe in the pattern.

The cam grooves 198 are of such form that the carry-in fingers are caused to pause momentarily when the selected new-warp thread has reached a position close to the sight opening, in order that the operator may observe whether the new-warp thread corresponds in color to the portion of the band 223 which is visible through the sight opening, and whether a single thread from each warp has been selected. If only one thread has been selected, or if the new-warp thread is of the wrong color, the operator lifts his hand from the lever 153, thereby stopping the travel of the carriage 136 and the operation of the mechanisms mounted on said carriage. The operator then introduces the required correction; if necessary, he operates either pair of selectors independently of the remainder of the mechanism in the manner fully disclosed in the Bingham & Parker application. Correction having been effected, the operator places his hand on the lever 153, whereupon the operation of the machine is resumed.

A color band is made up for each pattern. The band must be at least long enough to extend from the roller 224 to the roller 225 when said rollers are nearest each other, and may be as much longer as the pattern requires. The band may contain one or more of the "repeats" constituting the pattern. The ends of the band are suitably joined after the band has been placed upon the rollers 224 and 225. If desired, the band may be made of adhesive tape, the colored stripes consisting of pieces 223^a (Fig. 2) of colored paper or the like adhering to the coated side of the tape, and the ends of the bands being overlapped. In setting the band to accord with the warps, the operator may turn the roller 224 by means of the knurled flange 224^a (Fig. 2). When the band is to be moved backward, the pawl 231 may be held out of engagement with the

ratchet wheel 233 by means of the handle 231^a. While I have herein disclosed the invention in connection with a warp-uniting machine, it will be understood that the invention is applicable to other types of machines that operate upon warp threads.

I claim as my invention:

1. A warp-uniting machine having, in combination, a thread-uniter, for uniting the end portions of two warp threads, means for moving warp threads to the uniter, means providing a sight opening adjacent to the path of the warp threads, the thread-moving means being arranged to pause when the thread is adjacent to the sight opening, and indicating means visible through the sight opening.

2. A warp-uniting machine having, in combination, a thread-uniter for uniting the end portions of two warp threads, means for moving warp threads to the uniter, means providing a sight opening adjacent to the path of the threads, an endless color band a portion of which is visible through said sight opening, and means for moving the color band.

3. A warp-uniting machine having, in combination, a thread-uniter for uniting the end portions of two warp threads, means for moving warp threads to the uniter, means providing a sight opening adjacent to the path of the threads, and indicating means visible through said sight opening.

4. A warp-uniting machine having, in combination, a thread-uniter for uniting the end portions of two warp threads, means for laterally moving warp threads to the uniter, and color-indicating means adjacent to the path of the threads.

5. A warp-handling machine having, in combination, means for laterally moving warp threads, a plate located below the path of movement of the warp threads, said plate having a sight opening, and an endless band arranged for movement below the plate, said band carrying a series of colored elements.

6. A warp-handling machine having, in combination, means for laterally moving warp threads, a plate located below the path of movement of the warp threads, said plate having a sight opening below a point in the path of lateral movement of the threads, and color-indicating means visible through the sight opening for comparison with each laterally-moved thread.

7. A warp-handling machine having, in combination, a thread-selector for laterally moving individual warp threads, and an endless band arranged for movement adjacent to the selector, said band carrying a series of colored elements.

8. A warp-handling machine having, in combination, a thread selector for laterally moving individual warp threads, and color-

- indicating elements movable in an endless series past a point adjacent to the selector.
9. A warp-handling machine having, in combination, a thread-selector for laterally moving individual warp threads, means providing a sight opening adjacent to the selector, and color-indicating means visible through the sight opening.
10. A warp-handling machine having, in combination, a thread-selector for laterally moving individual warp threads, and a color-indicator movable in proximity to the thread selector.
11. A warp-uniting machine having, in combination, a knotter, means for laterally moving warp threads to the knotter, means providing a sight opening adjacent to the path of lateral movement of the threads, and indicating means visible through the sight opening.
12. A warp-uniting machine having, in combination, a knotter, means for laterally moving warp threads to the knotter, means providing a sight opening adjacent to the path of lateral movement of the threads, an endless color band, a portion of which is visible through said sight opening, and means for moving the color band.
13. A warp-uniting machine having, in combination, a knotter, means for laterally moving pairs of warp threads to the knotter, means providing a sight opening adjacent to the path of one thread of each pair, and indicating means visible through said sight opening.
14. A warp-uniting machine having, in combination, a knotter, means for moving pairs of warp threads to the knotter, each pair consisting of a new warp thread and an old warp thread, and shiftable color-indicating means adjacent to the path of the new warp threads.
15. A warp-handling machine having, in combination, means for supporting a warp, means for selecting threads singly and successively from the warp, and color-indicating means adjacent to the position assumed by successive selected threads.
16. A warp-handling machine having, in combination, means for supporting a warp, means for selecting threads singly and successively from the warp, the selecting means moving successive threads to a certain position, a plate located below the path of movement of the threads, said plate having a sight opening adjacent to the before-mentioned position of a selected thread, and color-indicating means visible through the sight opening.
17. A warp-handling machine having, in combination, means for supporting a warp, means for selecting threads singly and successively from the warp, the selecting means moving successive threads to a certain position, a plate located below the path of movement of the threads, said plate having a sight opening adjacent to the before-mentioned position of a selected thread, and an endless band arranged for movement below the plate, said band carrying a series of color elements which are visible through the sight opening.
18. A warp-handling machine having, in combination, means for supporting a transverse section of a warp, means for laterally moving warp threads away from the remainder of the threads composing said transverse section, and color-indicating means adjacent to the path of lateral movement of the threads.

In testimony whereof, I hereunto set my hand.

HOWARD D. COLMAN.
